CLAIM

The ornamental design for a child resistant storage device, as shown and described.

DESCRIPTION

FIG. 1 is a top perspective view of a child resistant storage device in the closed position;

FIG. 2 is a bottom perspective view thereof;

FIG. 3 is a front view thereof;

FIG. 4 is a right side view thereof;

FIG. 5 is a rear view thereof;

FIG. 6 is a top view thereof;

FIG. 7 is a bottom view thereof;

FIG. 8 is a top perspective view of the child resistant storage device in the open position;

FIG. 9 is a bottom perspective view thereof;

FIG. 10 is a right side view thereof;

FIG. 11 is a rear view thereof;

FIG. 12 is a front view thereof;

FIG. 13 is a top view thereof; and,

FIG. 14 is a bottom view thereof.

1 Claim, 10 Drawing Sheets
